UNITED STATES PATENT OFFICE.

FOREST A. PORTER AND FELIX SCHMIDT, OF CHICAGO, ILLINOIS.

VIOLIN-GUITAR.

Application filed September 26, 1927. Serial No. 222,114.

This invention relates to musical instruments and has for its object the combination of open strings to be played like a violin with a violin bow, together with other strings arranged in groups to produce the chords suitable to be played as accompaniment to the respective violin or melody strings.

Another object is to provide violin or melody strings arranged in pairs on opposite sides of the neck and at a suitable distance apart to facilitate the playing of one without likelihood of bowing more than one string at the same time to create a discord.

Another object is to provide violin or melody strings which extend from a tuning key on one side of the head, about a suitable shoulder, and back to a tuning key on the opposite side of the head, the one string providing two different tones when desired, by adjustment of the tuning thereof.

Another object is to provide suitable clips at the shoulders about which the violin or melody strings pass, which will form a sharp edge to hold the string, and which shall be bent backward at such an angle that the bow can slide upon it from one string to the next higher or lower without raising it from the string.

With the above and other objects in view, which will more particularly appear in the accompanying specification, we have shown and illustrated in the accompanying drawings, one embodiment of our invention, in which said drawings, similar numerals refer 35 to the same parts in the various drawings, and in which,

Figure 1 is a top plan view of one style of our invention.

Figure 2 is a side elevation, taken from 40 above in Figure 1, and showing the neck, strings and tuning keys on one side thereof.

Figure 3 is a detail view of one of the clips 15 employed at the various shoulders of the neck.

Figure 4 is a detail view of the clip 15 having a variation, in that a portion of the bent over part 16 is bent forward.

Figure 5 is an elevation of the attachment without the strings.

Figure 6 is a perspective view of a fragmentary portion of the invention showing the relationship of the clips and depressions without the strings.

Figure 7 is a view similar to Figure 6 show-

ing how the strings are associated with the 55 clips.

In the illustration shown in the accompanying drawing, 1 represents any usual form of sounding box over which strings may be stretched, as for guitar, zither or the like, and 60 this may be of the shape shown, or may be varied as best suits the purpose of the manufacturer. 2 represents chord strings attached to fixed pins at 3, and stretched over the bridges 4 and 5 and attached to the tuning 65 keys 6, 6 by means of which tuning keys the various strings 2 are tuned to the pitch required, as usual. These strings 2 are usually arranged in groups of four each, including one bass string tuned to the bass note of some 70 required chord, and the three other strings tuned each to one of the harmony notes in harmony with the bass note.

At some suitable portion of the sounding box 1, as at 7 we have provided a suitably 75 raised portion, forming a head 17, neck 10 and body portion 7 for use in holding the violin or melody strings 9, 9. At suitable locations along the upper edge of the portion 7, we have provided depressions 12, with the 80 vertical shoulders 13, gradually sloping forward, as shown. At the base of the shoulders 13 saw cuts at 14, 14 are provided to receive and retain the clips 15, 15 shown inserted therein. These clips 15, 15 are generally 85 made of some suitable thin metal, but may also be made of any other material adapted for the purpose. We have preferably made these clips 15, 15 the same height as the shoulder 13, or if required, they may project 90 slightly thereabove, and then gradually sloping backward at 16, until the rear edge is below the line of the strings attached on the shoulder next higher up.

The strings 9, 9 are mounted by attaching 95 one end to one of the tuning keys 11 on one side of the head 17, and then passed backward and around one of the shoulders 13, being passed at the rear of the clip 15 mounted at the respective shoulder, and underneath the 100 rearwardly extending portion 16 thereof, as shown, and then the string is passed forwardly over a bridge similar to 8, and the end attached to one of the tuning keys 11 on the side opposite to that to which the first 105 end had been attached.

By this construction, it will be readily seen that each string may serve the purpose of two

strings, being tuned to one pitch on one side of the head, and to another pitch on the reverse side, the contact with the clip 15 providing sufficient friction to prevent the string 5 from slipping and lowering the pitch of the side tuned to the higher pitch. It will also be seen that this style of construction does away with necessity of the fixed pins usually employed in this style of construction to attach the rear ends of the various strings. By employing the clips 15, of the shape as shown, the violin bow may be passed or slid from one string to the next higher or lower, or over several strings, without raising it 15 from the strings, which greatly facilitates bowing the instrument, and makes it much easier for beginners, and novices to play the instrument, than when difficult and complicated bowing is required, as on the usual violin, and similar instruments. It will also be seen that by mounting the strings upon opposite sides of the portion 7, as shown, and only two strings at the same portion, either string may be played, even by a novice, without 25 the usual danger of bowing both strings at once, creating the discord which frequently occur with beginners on the violin.

In the construction shown, we have preferably tuned the melody strings 9, 9, to the 30 succeeding notes of the scale, commencing with c at the rear left hand, each right hand string being one note higher, and each forward left hand string being one note above the next lower right hand string. By this 35 construction, the music may be played upon open strings, which require no fingering to vary the pitch as is required on violin style instruments, thus reducing the difficulty of playing and simplifying the general performance of the beginner and novice so that he may play creditably well without the infinite practice and pains required on the usual violin and similar instruments.

By placing our strings 9, 9 on opposite sides 45 of the portion 7, the strain or tension of the string on one side offsets the strain or tension on the other side, and even a very light construction for the portion 7 will sustain the tension of the strings, without fear of bending 50 from such tension, as is usual with the ordinary construction employed in similar instruments, with all of the strings positioned on one side of the body or neck.

While we have described our instrument as 55 being adapted to be played with an ordinary violin bow (not shown) as we believe the music produced by such means more attractive than that produced by any other means, yet it will be apparent that the melody strings 60 9, 9 may be picked in the manner similar to mandolin strings, or may be caused to give out their tones by any other means preferred by the player.

In the usual method of playing our said 65 instrument, the violin bow is held in the right

hand, and the melody strings 9, 9 are played in the order to produce the melody. At the same time, the chord strings 2, 2 are played with the left hand, the proper chord strings being played to produce the harmonious 70 chord for each melody string as played by the violin bow.

If it is desired, suitable letters or figures may be placed opposite the various melody 75 strings, and the various chord groups, to facilitate selection of the proper chord for each melody note, but as this forms no part of our present invention, we have not shown it herein.

To facilitate the retention of the melody 80 strings 9, 9 in their proper elevation, we have preferably made a slight indentation or notch 18 in the clips 15, 15, just beneath the bend and at the point where the strings 9, 9 pass therearound, and by placing the strings 9, 85 9 in these indentations, they are retained against movement in use or by accident. In Figure 4 we have shown a variation of the clip 15, in which the middle portion of the part 16 is bent forward, as shown 19. By 90 prick punching the clips at 20, as shown in Figure 3, a raised portion is formed on the rear side which facilitates holding the strings in normal position against movement or slipping up or down in use.

Having thus described our invention, what we claim and desire to secure by Letters Patent, is the following:—

1. In a musical instrument, the combination of a member forming a sounding box, 100 a raised member adjacent thereto forming a support for melody strings, said support having spaced depressions in its upper surface, tuning keys on both sides of the head of said support, a melody string extending from one tuning key on one side of the head along the side of the support back to the depression, across to the opposite side of the support and forward to a corresponding tuning key on opposite side of the head of said support member, substantially as shown and described.

2. A violin attachment for a zither or other like musical instrument, comprising a body portion having spaced depressions on the 115 upper surface thereof, one portion of said depression being vertical, a saw cut at the base of said vertical portion, a clip member in said saw cut extending upward to the top of the vertical portion of said depression, and then bent backward at an acute angle, tuning keys upon both sides of the head of said body portion, melody strings arranged in playing position opposite each depression consisting of a single string attached to a tuning key on one side of the head, passing backward around a vertical portion and over the clip adjacent said vertical member, and underneath the backward extending portion of said clip, and forward upon 125 130

the opposite side of said body portion, with the end attached to one of the corresponding tuning keys on the opposite side of said head, substantially as shown and for the purposes described.

3. In a musical instrument, the combination of a member forming a sounding board, accompaniment strings arranged adjacent said sounding board member, a support for melody strings arranged at one side of said sounding board member along a substantial portion of its length but projecting therebeyond and rising therefrom, said support having spaced depressions on its upper surface, and melody strings arranged in doubled relation adjacent each said depression upon both sides of said support.

4. A musical instrument comprising a member forming a sounding board having accompaniment strings arranged thereabove, a raised portion attached thereto having depressions in its upper surface, melody strings arranged on both sides of said raised portion in doubled relation, whereby sets of two playing strings are formed, said sets being arranged in playing position adjacent each said depression therein and means for tuning said sets.

5. A musical instrument comprising a sounding board, strings arranged in playing relation thereto, and a raised support extending beyond said sounding board and rising therefrom, said support having a plurality of depressions in its surface, strings

passing from one side of said support to the other via said depressions, each string thereby providing two playable portions, there being means for tuning each playable portion of each string.

6. In a musical instrument, an elongated member, a plurality of depressions in the upper surface thereof, strings arranged in playable relation to said depressions, and means to retain said strings in said playable relation.

7. In a musical instrument, an elongated member, a series of depressions in the upper surface thereof, vertical walls between said depressions, clips abutting said vertical walls, and strings passing from one side of said member around said clips to the other side of said member.

8. In a musical instrument, an elongated member, a series of depressions in the upper surface thereof, vertical walls between said depressions having slots extending from the base thereof into said member, string-holding clips in said slots, and strings passing from one side of said member around said clips to the other side of said member, said strings being tunably anchored at both ends, whereby each string provides two playing portions.

In testimony whereof, we have duly signed the foregoing specification.

FOREST A. PORTER.
FELIX SCHMIDT.
